SADAYOSHI NAKAHARA, OF NEW YORK, N. Y.

ROTARY CALENDAR

Application filed December 31, 1930. Serial No. 505,689.

This improvement relates more particularly to desk calendars mounted on a supporting base and having a casing, provided with sight openings adapted to show the day 5 of the week and the day of the month, which are adapted to be changed daily by simply turning a knurled head at one end of the casing which simultaneously rotates two cylinders, one of which carries the days and 10 the other has mounted thereon the numerals 1 to 31.

One object of the present improvement is to mount a cylinder carrying numerals representing the days of the month for simultaneous rotary and axial movement, the numeral 15 dates thereon being arranged about the cylinder so that they are brought into view by a combination of the two movements. A similar cylinder carrying the days of the 20 week is mounted for rotary movement only, and detent connections between the two cylinders are provided for effecting simultaneous rotation of both cylinders by turning one of them, the arrangement being such that independent rotation of the respective cylinders is obtained by holding one of the cylinders and turning the other cylinder, for 25 synchronizing the days of the week with the numerals representing the days of the month. 30 This independent movement of the cylinders needs to be done only at the beginning of each month, after which both cylinders are rotated in unison by turning one knurled head.

The preferred form of the improvement is 35 shown in the accompanying drawings, in which Fig. 1 is a vertical longitudinal section of the calendar; Fig. 2 is a vertical transverse section; Fig. 3 is a plan view of the cylinders removed from the casing with one 40 of the cylinders partially broken away and in section; Fig. 4 is a transverse vertical section of Fig. 3 through both cylinders at the notched end of the inner cylinder, and Fig. 5 is a front view of the calendar.

Referring to the drawings, it will be seen 45 that the rotary calendar comprises a cylinder 3 upon the outer surface of which the days of the month are shown spirally, as indicated in Fig. 3. The cylinder 3 telescopes into another cylinder 4 upon the outer sur-

face of which the days of the week (two sets) are mounted, as indicated in Fig. 3, the days of the week and the numerals of the monthly dates being adapted to show through sight openings 5 in the upper front portion of an 55 enclosing cylindrical casing 10, the sight openings being arranged in position for the best visibility.

Knurled heads are provided at each end of the casing 10 for rotating the cylinders 3 and 4, the knurled head 1 for rotating cylinder 3 being provided with axially extending rods 9, screw-threaded into the head 1 and passing through holes in the disc end 3a of the cylinder 3. This construction is adapted to permit axial or longitudinal movement of the cylinder 3 as it is rotated.

In order to effect the axial movement of the cylinder 3 simultaneously with rotary movement thereof, the disc end 3a is provided with a threaded central opening cooperating with a screw threaded rod 8, extending axially of both cylinders as shown in Figs. 1 and 3. The threads on the screw 8 are shown four to the pitch, the pitch being equal to 70 the space between centers of adjacent spirals of the numerals representing monthly dates 75 on the outer surface of the cylinder 3. This arrangement permits the use of finer threads on the screw while providing for the desired 80 axial movement of the cylinder.

In order to permit independent adjustment 85 and for simultaneous rotation of cylinders 3 and 4 and for axial movement of the monthly date cylinder 3, detent connecting means are provided between cylinders 3 and 4, properly spaced to align the days of the week with the days of the month, so that they may be properly displayed at the sight openings 5. For this purpose the left end of the cylinder 90 3 is provided with an outwardly extending flange, in which a plurality of notches 6 are cut, there being fourteen shown in the drawings, because two sets of week days on the cylinder 4 requires fourteen spaces. For co-operation with the notches 6 in the flange of the cylinder 3, there is arranged a resilient detent member 7 extending longitudinally of and parallel with the axis of the cylinder 4, said detent member being formed by a 95 100

narrow tongue cut out of the cylinder wall and bent inward, so that the edge thereof is adapted to engage one of the notches 6 and temporarily hold the two cylinders together for rotation in unison.

However, it will be seen that this detent connection between the cylinders 3 and 4 is also arranged to permit independent rotation of either of the cylinders (3 or 4) and 10 at the same time permit axial movement of the monthly date cylinder 3 relative to the cylinder 4, which rotates without axial movement.

In order to retain the rotating parts of 15 the calendar in proper relation, the knurled ends 1 and 2 are mounted for rotation upon the respective ends of the screw 8 and the latter is secured by means of screws in the ends thereof between supporting plates 11, 20 which are mounted upon the base block 13 and are provided with downwardly projecting bolts, passing through the base block and secured thereto by nuts 15, located in recesses on the underside of the base block, as will be 25 seen in Figs. 1 and 2. The casing cylinder 10 extends between the rotary knurled ends 1 and 2, the latter being provided with flanges extending over reduced ends of the casing cylinder 10, as will be seen in Fig. 1, the 30 casing cylinder being mounted on the base block 13 and held in proper position by downwardly projecting screw studs 14.

For displaying the month, a small casing with a rectangular window is mounted on 35 the base of the calendar and provided with cards or slips 16 having the months thereon, which may be changed each month.

In operation, the knurled end 1 is rotated forward or by a left turn to withdraw 40 the cylinder 3 from cylinder 4 to bring the monthly date cylinder 3 back to initial position so that the numeral 1 thereon will register with the small window 5 in the casing 10 and then the cylinder 3 should be held or 45 prevented from rotation by holding the knurled end 1 while the cylinder 4 is rotated by turning the knurled end 2, to which the cylinder 4 is soldered or otherwise secured. The detent connection (6-7) between the 50 two cylinders permits this independent adjustment in order to synchronize the weekly and monthly dates, or to bring the day of the week on which the first of the month falls into register with the sight openings 5 when 55 the numeral 1 of the cylinder 3 is in register with its sight opening 5. Thereafter, the detent connections 6 and 7 will cause both cylinders 3 and 4 to turn in unison to present the successive days of the week and days of 60 the month in proper sequence by simply turning one of the knurled ends, preferably the knurled end at the right hand end of the calendar.

I claim:

36 1. A rotary calendar comprising a cylind-

der mounted for simultaneous rotary and axial movement, the days of the month being arranged spirally on the outer surface thereof, a second cylinder mounted for rotation in a fixed axial position, the days of the week being arranged circumferentially on the outer surface of the second cylinder, the first cylinder telescoping into the second cylinder, an annular flange extending radially of said first cylinder and provided with notches equally spaced with the days of the week on said second cylinder, a resilient longitudinally extending pawl secured to and projecting from the said second cylinder into the path of said notched flange of the first cylinder for cooperation with said notches for aligning the days of the week with the days of the month and for temporarily locking both cylinders together for simultaneous rotation while permitting independent rotary adjustment between the cylinders by holding one cylinder and rotating the other in either direction, said aligning pawl being long enough axially to be effective in any position of axial movement of the first cylinder relative to the second cylinder.

2. The rotary calendar as in claim 1, wherein said telescoping cylinders are mounted within and for rotation about the axis of a horizontally disposed cylindrical casing having its ends closed by rotatable heads, one of said heads being provided with rods extending parallel with said axis into and adapted for rotating said first named cylinder, the rods permitting said axial movement of the cylinder and said axial movement is effected by a fixed screw threaded rod cooperating with a nut secured to said first named cylinder as the latter is rotated by said rods, said second cylinder being secured to the other rotary head for rotation in a fixed position.

3. A rotary calendar comprising a cylindrical casing provided with sight openings for the days of the week and the days of the month, a cylinder provided with a head forming one end of the casing and adapted for rotating said cylinder in fixed position, the days of the week being mounted on said cylinder for rotation into register with the corresponding sight opening, a second rotary cylinder adapted to telescopingly slide into the first named cylinder and mounted for simultaneous axial movement as it is rotated to bring the days of the month into register with said other sight opening, a rotatable head forming the other end of the casing and provided with means for rotating said second cylinder while permitting said axial movement, means for effecting said axial movement of said second cylinder, and resilient pawl and notch connecting means between the two cylinders for effecting rotation in unison of both cylinders by rotating one

of them, said detent connecting means being adapted to permit simultaneous independent relative rotation of the cylinders in either direction for synchronizing the weekly and 5 monthly dates at the beginning of the month, after which the cylinders are rotated in unison.
